UNITED STATES PATENT OFFICE.

TIMOTHY F. EATON AND CHARLES E. EATON, OF BROCKTON, MASSACHUSETTS.

ARCH-SHANK FOR SHOE-SOLES.

No. 921,379.

Specification of Letters Patent.

Patented May 11, 1909.

Application filed January 2, 1909. Serial No. 470,551.

To all whom it may concern:

Be it known that we, TIMOTHY F. EATON and CHARLES E. EATON, citizens of the United States, and residents of Montello, 5 Brockton, in the county of Plymouth and State of Massachusetts, have invented a new and Improved Arch-Shank for Shoe-Soles, of which the following is a full, clear, and exact description.

10 The invention is an improvement in arch supporting shanks as are attached to the inside of the outer soles of shoes, and is designed to replace the customary wood and steel shanks and afford a strong economical 15 support which is easily and securely applied.

To this end the invention consists of an arch supporting shank of sheet metal, having tongues stamped therefrom to secure the shank to the shoe sole, with the tongues arranged near the opposite ends of the shank, and the points thereof as stamped out, directed outwardly, and longitudinal ribs pressed in the shank from its under side and respectively arranged at the opposite sides of 25 the tongues.

Reference is to be had to the accompanying drawings forming a part of this specification, in which similar characters of reference indicate corresponding parts in all the views.

30 Figure 1 is a perspective view of an outer shoe sole with our improved arch supporting shank applied thereto; Fig. 2 is a side view of a shoe, partly in longitudinal central section, having our improved arch supporting shank; 35 Fig. 3 is a plan of the shank removed from the sole; and Fig. 4 is a cross-section of the shank substantially on the line 4—4 of Fig. 3.

We construct our improved arch supporting shank 5 of sheet metal, preferably of a 40 springy nature, and shaped to conform to the sole of the shoe at the arch but of substantially less width, thus the side edges of the shank are convex, the heel edge rounding and the front edge extending at an angle to the 45 median line of the shank, or otherwise suitably shaped. From the body of the shank near each end is stamped a tongue 6, the points of the tongue being directed toward the ends at the time of stamping out, and the

50 tongues afterward bent downwardly at approximately right angles to the shank, as shown in Fig. 4. The shank is stiffened and strengthened by pressing therein from the under side, longitudinal ribs 7, which are re-

spectively arranged at opposite sides of the 55 tongues and terminate short of the ends of the shank, as shown in Fig. 3, whereby these ends may be pressed closely to the sole of the shoe.

In applying the shank to an outer shoe sole 60 8, openings or slots are formed in the sole a distance apart equal to the distance between the tongues of the shank and at points to properly locate the shank on the arch. The tongues are passed through these slots from 65 the upper face of the sole, and the points of the tongues clenched by bending them toward each other into engagement with the under side of the sole, as shown in Fig. 2, thus securely connecting the shank and sole together. This manner of uniting these parts dispenses with the use of such devices as screws, nails, etc., and avoids possible chance of the plate working loose. Any strain tending to shift the shank forwardly or rearwardly will be effectually resisted by the rear 75 and forward tongues respectively.

The shank may be arched at the time of arching the sole and will occupy the position in the finished shoe as shown in Fig. 2, the 80 ribs 7 not only serving to strengthen and stiffen the shank but also engaging in the leather or other material above and preventing the shank from working sidewise.

Having thus described our invention, we 85 claim as new and desire to secure by Letters Patent:

The combination of an outer shoe sole, an arch shank of sheet material having tongues stamped therefrom, with the points of the 90 tongues as stamped out, respectively directed toward the opposite ends of the shank, and ribs pressed longitudinally into the shank from the under face thereof and arranged at opposite sides of the tongues, said tongues 95 being bent downwardly and passed through the outer shoe sole, and bent inwardly toward each other against the bottom of the sole to secure the shank to the upper face of the sole.

In testimony whereof we have signed our names to this specification in the presence of two subscribing witnesses.

TIMOTHY F. EATON.
CHARLES E. EATON.
